UNITED STATES PATENT OFFICE.

LAURENCE E. TOPHAM, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

DRIVING AND STOPPING MECHANISM.

1,099,327.

Specification of Letters Patent.

Patented June 9, 1914.

Application filed August 5, 1912. Serial No. 713,360.

To all whom it may concern:

Be it known that I, LAURENCE E. TOPHAM, a citizen of the United States, residing at Swampscott, in the county of Essex and State of Massachusetts, have invented certain new and useful Improvements in Driving and Stopping Mechanism; and I do hereby declare the following to be a full, clear, and exact description of the invention, such as will enable others skilled in the art to which it appertains to make and use the same.

The invention relates to driving and stopping mechanism adapted for use upon high speed machines.

The object of the invention is to provide a novel and improved mechanism which will act in a uniformly reliable manner upon the throwing out of the main driving mechanism to arrest the forward movement of the machine or driven mechanism at a predetermined point in its operation and then move it back to a predetermined point.

To this end the invention contemplates the provision of a slow speed forward driving mechanism and a low speed reverse driving mechanism which are thrown into action successively when the high speed forward drive is thrown out, and which act to gradually overcome the inertia of the driven parts, to continue the forward movement at a slow speed, to reverse the movement at a predetermined point, and to finally bring the parts to rest in a predetermined position. The provision of slow speed driving mechanisms for continuing the forward movement of the driven parts to the point where the reverse takes place, and for returning the parts to final stopping position, insures a uniform reversing and stopping of the parts unaffected by variations in the speed of the parts when the reversing and stopping mechanism is thrown into action.

The various features of the invention will be readily understood from an inspection of the accompanying drawings, and the following detailed description of the construction illustrated therein.

In the drawings, Figure 1 is a side elevation of a welt and turn sewing machine provided with a driving and stopping mechanism embodying the invention in its preferred form; Fig. 2 is a front elevation showing the driving and stopping mecha-

nism on a larger scale; Fig. 3 is a vertical longitudinal section through the driving and stopping mechanism; Fig. 4 is an end elevation looking toward the right in Fig. 2; and Fig. 5 is a detail sectional view on line 5—5, Fig. 2.

The mechanism shown in the drawings is especially designed for use upon a welt and turn machine, and is constructed to stop the forward movement of the machine after the needle has advanced sufficiently to cast off its loop, and to then turn the machine back to a point where the needle is retracted and the parts of the machine in proper position for the removal and insertion of a shoe. It will be understood, however, that this mechanism is not confined in its application to a machine of this character, but may be used in other machines and in other relations where it is desirable to give the machine or driven parts a reverse movement upon stopping the machine.

As shown in the drawings, the cam shaft of the sewing machine is driven through a shaft 1, the lower end of which is journaled in a casing 2, and is provided with a bevel gear 3 engaging a driving gear 4. The gear 4 is secured to a sleeve 5 loosely mounted on a shaft 6, and carries one member 7 of the main driving clutch. The other member 8 of the clutch is carried by a driving pulley 9 mounted to turn freely about the sleeve 5. The casing 2 is secured upon the end of a rod 10 which is mounted to slide in the frame of the machine, and is moved longitudinally through a mechanism controlled by a starting and stopping treadle 11. The rod 10 is acted upon by a spring 12 which tends to move it in a direction to disengage the members of the driving clutch. When the machine is to be started, the treadle is depressed, thus drawing down a wedge 13 which acts against a collar 14 on the rod 10 and forces the rod in a direction to engage the members of the driving clutch. So long as the operator keeps his foot on the treadle 100 the machine is driven through the main driving clutch at a speed depending upon the force with which the operator presses the members of the clutch together. When the operator removes his foot from the treadle, the treadle and wedge 13 are raised by a spring 15, allowing the members of the clutch to be disengaged by the spring 12, and

thus throwing the main driving clutch out of operation.

When the main driving mechanism is thrown out, the slow speed driving and reversing mechanism is thrown into operation. In the construction shown this mechanism comprises differential gearing driven from the driving pulley 9 and connected with the driving gear 4 to transmit a slow motion thereto in either a forward or reverse direction. As shown, the driving pulley carries a shaft 16 upon which are secured three pinions 17, 18 and 19, of different sizes. The long faced pinion 17 engages a pinion 20 formed on the end of the sleeve 5 to which the driving gear 4 is secured, the pinion 18 engages a pinion 21 formed on a sleeve 22 which surrounds the shaft 6, and the pinion 19 engages a pinion 23 formed on the hub of a brake drum 24 which is loosely mounted on the sleeve 22. The sleeve 22 is journaled in a fixed bearing 25, and at its outer end carries a brake drum 26. The brake drum 24 is provided with a flange surrounding clutch shoes 27, and the brake drum 26 is provided with a similar flange surrounding clutch shoes 28. The clutch shoes 27 and 28 are pivoted on fixed pivots indicated at 29 in Fig. 4, and the free ends 30 of the clutch shoes carry bearing pieces 31 adapted to engage the flattened ends 32 of a rock shaft 33. When the rock shaft is held in mid-position, as indicated in Fig. 4, both sets of clutch shoes are contracted by 35 their spring 33, and the drums 24 and 26 are free to rotate with the pulley 9. The rock shaft is held in this position during the normal running of the machine, and so long as the operator keeps his foot upon 40 the treadle and holds the members of the main driving clutch in engagement, the differential gearing and drums 24 and 26 travel with the driving pulley 9.

When the operator removes his foot from 45 the treadle to throw the main driving clutch out of operation, the mechanism for actuating the rock shaft 32 to successively expand the clutch shoes 27 and 28, and thus throw the differential gearing into operation, is 50 rendered active. The devices for operating the rock shaft comprise a sleeve 34 mounted to turn about a fixed shaft 35, and provided with an arm 36 which is connected through an expansible spring link 37 with 55 an arm 38 on the rock shaft. The sleeve is connected to a collar 39 on the shaft 35 by a torsional spring 40 which tends to rock the sleeve in the direction of the arrow in Fig. 4. The sleeve is retained in normal position 60 against the tension of the spring by a latch 41 arranged to engage a block 42 which is secured to an arm 43 projecting from the sleeve. The latch is mounted on a fixed pivot 44, and is provided with an arm 45 65 which is connected by a yielding expansible

link 46 with the block 42. When the sleeve 34 is rocked in a direction opposite to that indicated by the arrow in Fig. 4 to expand the clutch shoes 27, the link 46 acts to swing the latch 41 out from beneath the block 42. 70 When this takes place the latch is prevented from returning into position beneath the block 42 by a second latch slide 47 which engages a notch 48 in the hub of the latch. The latch slide 47 is mounted in a fixed bearing, and is pressed upward by a spring 49. After the latch 41 has been swung out of active position and latched in this position, the sleeve 34 is free to move in the direction of the arrow beyond the position 80 indicated in Fig. 4, and to thus expand the clutch shoes 28. When this takes place the end of the block 42 strikes the upper end of the latch slide 47, depressing the slide and releasing the latch 41 so that it swings 85 in ready to snap under the block 42 when the sleeve 34 is returned to mid-position. The mechanism for rocking the sleeve 34 to successively actuate the clutch shoes 27 and 28 comprises a lever 50 provided with 90 a hub 51 loosely mounted on the shaft 35, and connected by a forked projection 52 with the casing 2, so that the lever moves longitudinally of the shaft 35 with the casing and driving gear 4. The rear end of 95 the lever carries a roll 53 engaging a cam groove 54 formed in the rear face of the clutch member 7. The lever is provided on its under side with a bearing surface 55 arranged to coöperate with the upper end of 100 an arm 56 which is mounted on a second arm 57 projecting from the sleeve 34. The arm 56 is secured on a rock shaft 58 mounted in the lower end of the arm 57, and is held by a spring 59 against a stop 60 on 105 the arm 57. The lever 50 is so arranged with relation to the arm 56 that when the members of the driving clutch are in engagement, the lever is to the left of the arm in Fig. 2. During the normal running 110 of the machine, therefore, the lever 50 rides idly against the outer surface of the cam groove 54, the weight of the lever being supported by the cam groove. When the rod 10 and casing 2 move toward the right 115 to disengage the members of the driving clutch, the lever 50 is also moved toward the right, and if the roll 53 on the end of the lever does not happen to be in a low part 54^a of the cam groove 54, the side of 120 the lever will strike the arm 56, and the arm will yield and ride against the side of the lever until the roll comes to a low part 54^a. The arm 56 will then snap under the lever 50, and as the lever rides up on a high part 54^b of the cam groove the lever 125 will engage the arm 56 and swing the sleeve 34 in a direction opposite to that indicated by the arrow in Fig. 4, thus expanding the clutch shoes 27. 130

When the clutch shoes are expanded there will be more or less slip between the clutch shoes and the brake drum 24, so that these parts, in connection with the differential gearing, will act as a friction brake to gradually overcome the momentum of the moving parts until the speed of the driven parts is the same as that which will be given to them by the differential gearing. When the slip between the drum 24 and clutch shoes 27 ceases, and the drum comes to rest, the pinions carried by the driving pulley 9 will rotate around the gear 23, and since the gear 23 is smaller than the gear 20, the driving gear 4 will be driven in a forward direction at a slow speed. The slow forward speed of the driving gear and parts driven therefrom will continue until the roll 53 on the lever 50 reaches the end 54^c of the high part 54^b of the cam groove, when the roll will drop off of the end of the high part and enter the lowest part 54^a of the cam. This movement of the lever will rock the sleeve 34 in the direction of the arrow, Fig. 4, beyond its mid-position, thus releasing the clutch shoes 27 and expanding the clutch shoes 28. This frees the drum 24 and arrests the movement of the drum 26 and its connected gear 21. The gears carried by the driving pulley 9 will now rotate about the gear 21, and since this gear is larger than the gear 20, the forward rotation of the driving gear 4 will be arrested, and the gear rotated at a slow speed in a reverse direction. As the driven parts are moving at a slow speed when the clutch shoes 27 are released and the clutch shoes 28 expanded, there will be practically no slip between the clutch shoes 28 and drum 26, and the reversal of the driving gear and parts connected therewith will be uniformly effected at a predetermined point dependent upon the timing of the cam 54. The throwing into operation of the slow speed drive will be effected at a predetermined point dependent upon the location of the low part 54^a and high part 54^b of the cam, and the cam is so arranged that the throwing in of this mechanism is effected at a point sufficiently in advance of the throwing in of the reversing mechanism to insure an adequate braking interval during which the speed of the driven parts may be gradually reduced without undue shock or jar by the braking action of the slow speed forward drive. When the direction of rotation of the driving gear is reversed, as above described, the roll 53 on the lever 50 rides up the part 54^a of the cam groove 54, returning the rock shaft 32 to normal position, and disengaging the clutch shoes 28. The momentum of the machine then brings the end 54^c of the cam groove into engagement with the roll, so that the parts are finally brought to rest in a predetermined position. The parts are

now in normal position, ready to effect their functions when the main driving mechanism is again thrown out of operation.

In order to prevent a partial engagement of the lever 50 and arm 56 before the treadle operated wedge 13 is raised sufficiently to enable the full engagement of the arm and lever, a latch 61 is provided for holding the rod 10 and casing 2 against movement toward the right in Fig. 1 until the wedge has nearly completed its upward movement. This latch is pivoted to the collar 14, and is arranged to engage the end of an adjustable stop screw 62. The latch is arranged in the path of a pin 63 projecting from the wedge 13, and the pin is so arranged that it engages and operates the latch as the wedge completes its upward movement. During the normal running of the machine the operator may manipulate the treadle to vary the pressure between the members of the driving clutch, or to disengage the members of the clutch without danger of coupling the lever 50 with the devices for controlling the slowing down and reversing of the machine, since the latch 61 prevents a longitudinal movement of the rod 10 sufficient to bring the lever 50 into engagement with the arm 56. The latch also prevents a gradual movement of the lever into position to engage the arm 56, which might result in a partial coupling of the parts together and then a disconnection of the parts before the arm fully engaged the lever. The latch holds the parts against longitudinal movement until the wedge has nearly completed its upward movement, and then when the latch is released the spring 12 quickly shifts the parts into position to fully engage the lever and arm.

While it is preferred to employ the construction and arrangement of parts shown and described, it will be understood that this construction and arrangement is not essential to the broader features of the invention, and may be varied and modified without departing therefrom.

Having explained the nature and object of the invention, and specifically described one form of mechanism in which it may be embodied, what is claimed is:—

1. A driving and stopping mechanism, having, in combination, a main high speed driving mechanism, low speed forward driving mechanism, reverse driving mechanism, and automatic mechanism for rendering the low speed forward and reversing driving mechanisms successively active when the main driving mechanism is thrown out.

2. A driving and stopping mechanism, having, in combination, a main high speed driving mechanism, a low speed forward driving mechanism constructed to act as a friction brake when first thrown into operation and to then act to continue the forward

motion at a low speed, a reverse driving mechanism, and mechanism for rendering the low speed driving and reversing mechanisms successively active when the main driving mechanism is thrown out.

5. A driving and stopping mechanism, having, in combination, a main driving mechanism under starting and stopping control of the operator, low speed forward driving mechanism, reversing mechanism, and automatic mechanism for rendering the low speed forward and reverse driving mechanisms successively active when the main driving mechanism is thrown out.

10. 4. A driving and stopping mechanism, having, in combination, a main driving mechanism under starting and stopping control of the operator, low speed forward driving and reversing mechanisms, and mechanism timed by the driven parts for throwing the slow speed driving and reversing mechanisms successively into action and for throwing the reverse drive out.

15. 5. A driving and stopping mechanism, having, in combination, a main driving mechanism under starting and stopping control of the operator, low speed forward driving and reversing mechanisms, a timing cam and connections operating when the main 20 drive is thrown out to throw in the low speed forward drive, throw out this drive and throw in the reverse drive, and finally throw out the reverse drive.

25. 6. A driving and stopping mechanism, having in combination, a treadle controlled main driving mechanism, a low speed driving mechanism, mechanism for throwing in the low speed driving mechanism including coupling members which are engaged upon 30 the release of the treadle, and devices for preventing the engagement of the coupling members until the treadle has moved sufficiently to allow their complete engagement.

35. 7. A driving and stopping mechanism, having, in combination, a main driving clutch under control of the operator, a treadle for controlling the main driving clutch, a low speed driving and stopping mechanism, and means rendered active by 40 the final clutch disengaging movement of the

treadle for throwing the low speed driving and stopping mechanism into action.

8. A driving and stopping mechanism, having, in combination, a main driving mechanism, a low speed forward driving mechanism including friction clutch members which act as a friction brake when first engaged, mechanism for engaging the clutch members when the main driving mechanism is thrown out, a reverse driving mechanism, and mechanism for disengaging the clutch members and throwing in the reverse driving mechanism.

10. 9. A driving and stopping mechanism, having, in combination, a main driving mechanism, low speed forward driving and reversing mechanisms, a timing cam connected with the driven parts, and connections normally inactive and rendered active upon the throwing out of the main driving 65 mechanism for successively throwing in the low speed forward driving and reversing mechanisms.

15. 10. A driving and stopping mechanism, having, in combination, a driving pulley, a driving clutch connected with the pulley, three pinions of different sizes mounted concentric with the pulley, three connected pinions carried by the pulley and engaging the concentric pinions, brake drums connected 70 to two of the concentric pinions, clutch shoes for engaging the brake drums, and mechanism for successively actuating the clutch shoes when the main driving clutch is thrown 75 out.

20. 11. A driving and stopping mechanism, having, in combination, a main driving mechanism, a low speed driving and stopping mechanism, a cam connected with the driven parts, a lever operated by the cam, 80 devices for actuating the low speed driving and stopping mechanism normally disconnected from the lever, and means for connecting the devices with the lever when the main driving mechanism is thrown out.
